CASEMENT WINDOW SCREEN

Harry H. Everhard, Canton, Ohio

Application June 22, 1935, Serial No. 27,907

9 Claims. (Cl. 156—14)

The invention relates generally to the construction of screens for casement windows, and more particularly to screen construction adapted to be detachably mounted on standard metal casement windows with great facility.

The initial installation of prior screen constructions, on standard metal casement windows of various types, always has been a difficult and tedious task requiring the services of a skilled workman and the drilling and tapping of holes in the casement frame, as well as the use of screws, bolts and other attaching devices requiring suitable tools.

In some types of standard casement windows the casement frame projects only a very slight distance from the window frame, so that an extremely narrow margin of the frame is available for mounting attaching devices, and for screen frame overlap.

Moreover, after such prior screen constructions have been installed on the casement frames, it is slow and troublesome work to remove and replace the same for washing the window or for any other purpose, because the bolts or other attaching devices have to be loosened and tightened, again requiring tools.

It is therefore an object of the present invention to provide improved detachable screen mounting means which can easily be applied to a standard metal casement frame without the aid of any tools, and without in any way altering the casement frame.

Another object is to provide a simple screen frame construction which is adapted to be quickly and easily attached to or detached from the improved screen attaching means on the frame without any tools, by the most inexperienced persons.

A further object is to provide improved means for detachably mounting and locking a screen on a casement frame in screen tight position.

Another object is to provide a screen construction for metal casement windows having improved detachable mounting means capable of adjustment for compensating for variations in the casement frame or the screen frame.

A still further object is to provide improved screen construction capable of being mounted on the inside of a casement window frame for quick attachment thereto and quick detachment therefrom, where the casement frame provides a minimum of overlap for the screen frame.

These and other objects are attained by the novel construction comprising the present invention, which construction is simple and economical

to manufacture, easy to install and remove, and which presents a neat and pleasing appearance when installed.

In general terms, the present construction includes resilient clips which can be snapped on the casement frame, and a screen frame adapted to cover the usual window fastenings on the casement frame and having means for detachably mounting the screen frame on the clips.

The invention resides in the novel construction, arrangement and combination of parts, which are herein described and illustrated, and defined in the appended claims.

Referring to the drawings forming part hereof,

Figure 1 is an elevational view of one standard type of metal casement window viewed from the room side, having the improved screen mounted thereon;

Fig. 2 is an enlarged broken sectional view thereof as on line 2—2, Fig. 1, showing adjoining portions of the building wall;

Fig. 3 is an elevational view similar to Fig. 1 of another standard type of metal casement window having the improved screen mounted thereon;

Fig. 4 is a vertical sectional view similar to Fig. 2, showing the improved screen in the position of being attached to or detached from the casement frame;

Fig. 5 is a fragmentary plan view of a top portion of the improved screen frame, showing the latch thereon;

Fig. 6 is an elevational view thereof, looking toward the room side of the screen;

Fig. 7 is a detached perspective view of one of the improved clips;

Fig. 8 is an end view thereof;

Fig. 9 is a fragmentary plan view of one of the improved clips positioned on the metal casement frame; and

Fig. 10 is an elevational view thereof viewed from the room side of the frame.

Similar numerals refer to similar parts throughout the drawings.

The casement window shown in Figs. 1 and 2 is a standard metal casement of ordinary type, and is shown mounted in a building wall of brick veneer construction. The casement frame 11 may be substantially Z-shaped in cross section, and is secured in the window frame in a usual manner.

The head member 12 of the casement frame abuts the surround piece 13 which backs up the lintel 14 supporting the brick veneer 15, and the sill member 16 is supported on the brick sill 17.

The sash frame 18 may be of similar construction, having the outer flange 19 for overlapping the outer flange 20 of the casement frame, and being adapted to swing to the outside of the building. The inner flange 21 of the sash frame normally abuts the inner flange 22 of the casement frame, when the window is closed.

The improved screen frame indicated generally at 23 is adapted to fit on the inner or room side of the casement frame, within the usual inside trim and stool members 24 and 25, respectively, of the window frame. The screen frame 23 is preferably of all metal construction, having the channel portions 26 in which the screening 27 is secured, and an inturned flange 28 extending continuously around the four sides of the screen frame.

The screening 27 may be tightly held or clamped in the channel portions 26 by means of retaining rods 29, in a usual manner; and the inner edge of the flange 28 is adapted to abut the room side of flange 22 of the casement frame 11.

The improved means for detachably mounting the screen frame 23 on the casement frame 11 preferably includes clips 30. As best shown in Figs. 7 and 8, each clip has a resilient U-shaped portion 31 (inverted as viewed in Figs. 7 and 8) adapted to be snapped on the inner flange 22 of the casement frame, in the manner indicated in Figs. 2, 4, 9 and 10.

At one side of the U-shaped portion 31 of each clip is formed a box like portion 32 having a slot cut in the upper side thereof to form a socket 33, and the clips are positioned on the flange 22 of the casement frame so that the portion 32 is at the room side of said flange, as indicated in the drawings.

The improved clips 30 are snapped on opposite sides of the casement frame when the window is open, preferably one clip at the center of the head member 12, and two clips at positions spaced longitudinally on the sill member 16, as shown in Figs. 1 and 3; and the sockets 33 of opposite clips open toward each other.

The improved means on the screen frame 23 for detachably locking it to the clips 30 for mounting the screen frame on the casement frame, preferably includes a latch 35 in the upper portion of the screen frame and adapted for engaging in the socket 33 of the clip 30 mounted on the head member 12 of the casement frame.

The bottom portion of the screen frame 23 preferably has adjustable projections indicated at 36 for entering the sockets 33 of the clips 30 which are mounted on the sill member 16 of the casement frame.

The latch 35 may be a single piece of metal extending through the slot 37 in the upper channel portion 26 of the screen frame, and the latch 35 is provided with an angular finger piece 38 at its room side end, and with a hook 39 at its other end. The continuous flange 28 is notched out at its inner edge portion as at 40, to permit the hook 39 to pass upward therethrough.

Preferably, a positioning plate 41 is secured to the flange 28 above the latch 35, and the plate 41 is provided with a rectangular notch 42, opening at the inner edge of the flange 28, said rectangular notch being adapted to fit around the box like portion 32 of the clip 30 when the screen frame is mounted on the casement frame.

The notch 40 in flange 28 registers with notch 42 in plate 41, and when the notch 42 is positioned around the box like portion of clip 30,

the socket 33 of the clip registers with notch 40, so that the hook 39 of the latch may engage in said socket and lock the screen frame against the casement frame.

The finger piece 38 of the latch may be enlarged at its entrance to the slot 37 in the screen frame to provide stop shoulders 44, and a strengthening plate 45 may be secured on the channel portion 26 around the slot 37 for abutting said shoulders to limit releasing movement of the latch.

A spring 46 may be interposed between the latch 35 and the bottom of the channel portion 26 for urging the latch toward the closed position shown in Fig. 2.

The adjustable projections 36 for entering the sockets 33 of the clips 30 mounted on the sill member 16 of the casement frame, may be studs or bolts projecting through the flange 28 at the bottom of the screen frame. The heads of the bolts 36 are adapted to enter the sockets 33 for holding the bottom of the screen frame in place against the casement frame. Each bolt 36 is threaded through a plate 48 secured on the inside of flange 28, and a lock nut 49 is screwed on the inner end of the bolt, so that the length thereof which projects below flange 28 may be adjusted to meet variations in the screen frame and casement frame.

In installing the improved casement window 30 screen on a standard type of casement window, the three clips 30 are first snapped on the inner flange 22 of the casement frame, with the fingers, the sash frame 18 being swung open; one clip being positioned at the central portion laterally of the head member, and two clips being spaced on the sill member substantially as shown in Fig. 1. The screen frame may then be positioned against the room side of the casement frame by entering the heads of bolts 36 in the sockets 33 of the lower clips 30, in the manner shown in Fig. 4, after first sliding the clips along the flange 22, if necessary in order to have the sockets register with the bolts 36.

After the heads of bolts 36 are entered in the sockets 33 of the lower clips 30 the operator grasps the finger piece 38 of latch 35 and lifts upwardly thereon to lower the hook 39 thereof, as shown in Fig. 4. The upper portion of the screen frame may then be moved into position with the inner edge of flange 28 abutting the flange 22 of the casement frame, and with the notch 42 of the positioning plate 41 fitting around the box portion 32 of upper clip 30. The latch 35 is then released, and the spring 46 returns the same to closed position with the hook 39 engaged in the socket 33 of the clip, to lock the screen frame against the flange 22 in screen tight position. Obviously, the upper clip 30 may be slid along the flange 22 of the head member 12 in order to make the box portion 32 register with the notch 42, if necessary.

In order to remove the screen frame from the window for washing windows, or for the winter season, it is only necessary for the operator to lift the latch 35, and the screen frame may be removed by pulling the top of the same outwardly and upwardly to withdraw the heads of bolts 36 from the lower sockets 33.

As shown in Fig. 1, where the operating handle 50 for the casement window is located in the center of the height thereof, the screen is provided with a horizontally sliding panel indicated at 51, which remains open when the window is

closed so that the handle 50 projects through the screening.

As shown in Fig. 3, where the casement window is of the standard type having the operating handle 50' located below the center of the height of the window, the lower part of the screen proper may be constructed as a vertically sliding panel indicated at 52, which is kept open, as shown, when the window is closed to accommodate the handle 50. Otherwise, the construction of the improved screen frame and screen frame mounting means is identical with that in Figs. 1 and 2.

Where the casement window is under frame operated, that is, where the locking handle and operating lever works through the fixed casement frame, there is unobstructed space for lapsing the improved screen frame all around, and the improved screen may be made in a single panel, full size.

The present improved casement window screen may be equally well applied to casement windows where the sash are equipped with adjusting braces at the sill, by providing a metal cover with a hinged front for the adjusters.

The improved clips provide means for detachably mounting the screen on standard metal casement windows of various types, without requiring the services of a skilled workman, or the drilling, tapping or any other operation on the casement frame, requiring tools; because the clips may be snapped on with the fingers.

Moreover, the clips do not have to be accurately located on the casement frame before the screen is applied, because they can be slid on the frame with the fingers, as required when the screen is attached.

The improved clips are all alike, and therefore interchangeable, consequently involving a minimum of manufacturing cost, and saving trouble in installation.

Furthermore, when the screen is removed for the winter season, the clips may be removed easily from the casement frame, without the use of tools, so that the unscreened window presents the same appearance as before the screen was initially installed, because the casement frame has not been disfigured in any way.

The present screen frame and clips are simple and economical to manufacture, and may be installed or removed in a few seconds by the most inexperienced person without the aid of any tools.

When installed, the improved screen presents a neat and pleasing appearance.

The present improved casement window screens can be installed on casement windows where the casement frame projects such a slight distance from the window frame as to preclude attaching screens of prior constructions, because the improved screen frame requires only $\frac{1}{4}$ " all-around for overlap on the casement frame, and the sill or frame may be slightly cut or notched to allow the improved clips to be snapped on the casement frame.

I claim:

1. In a metal casement window frame, clip means detachably mounted on said casement frame, and means on a screen frame for detachably locking the screen frame to said clip means. 5

2. In a metal casement window frame, clip means detachably mounted on said casement frame, and means on a screen frame for detachably locking the screen frame to said clip means, said locking means including a latch and adjustable clip engaging means.

3. In a metal casement window frame, means detachably locking a screen frame to said casement frame, said locking means including a spring clip on the casement frame and latch 15 means on the screen frame detachably interlocked with said clip.

4. In a metal casement window frame, means detachably locking a screen frame to said casement frame, said locking means including a 20 spring clip on the casement frame and having a socket therein, and an adjustable projection on the screen frame engaged in said socket.

5. In a metal casement window frame, clips detachably mounted on opposite sides of said casement frame and having sockets therein, and means detachably locking a screen frame to said clips, said locking means including a projection on the screen frame entered in the socket of one of the clips, and a latch detachably interlocked 30 with an opposite clip.

6. In a metal casement window frame, clips detachably mounted on opposite sides of said casement frame and having sockets therein, and means detachably locking a screen frame to said 35 clips, said locking means including an adjustable projection on the screen frame entered in the socket of one of the clips, and a latch detachably interlocked with an opposite clip.

7. In a metal casement window frame, clips 40 detachably mounted on opposite sides of said casement frame, and means on a screen frame detachably locking the screen frame to said clips, said locking means including a latch engaging one of the clips and an adjustable projection en- 45 gaging an opposite clip.

8. In a metal casement window frame, clips detachably mounted on opposite sides of said casement frame and having sockets therein, and means on a screen frame detachably locking the 50 screen frame to said clips, said locking means including a latch engaged in the socket of one of the clips and a projection engaged in the socket of an opposite clip.

9. In metal casement window frame screen 55 construction, a continuous screen frame flange having its inner edge abutting a casement frame, clip means detachably mounted on said casement frame, and means on said screen frame flange detachably locking the flange to said clip means. 60

HARRY H. EVERHARD.
